KNITTING METHOD

Nicholas F. Lahr, St. Joseph, Mich., assignor to
 Cooper, Wells & Co., St. Joseph, Mich., a corpora-
 ration of Michigan

Application June 22, 1939, Serial No. 280,580

1 Claim. (Cl. 66—96)

This invention relates to a knitting method and article and has particular application to full-fashioned hosiery. It is understood, of course, that the method and article may be applied to related fields where knitting with relatively fine 5 yarn or thread is effected.

In women's hosiery, particularly the full-fashioned variety, considerable difficulty has been encountered due to the fact that the knitted material is subjected to considerable strain at the knee when the wearer sits down. Hosiery of this character is made of relatively fine silk thread with a high twist. In addition to the ordinary stretching which the fabric must undergo, the 10 extra stretching due to bending of the leg at the knee while maintaining the stocking taut has resulted in straining the threads beyond their limit causing such threads to break and starting runs.

20 Various expedients have been relied upon to introduce an elastic and stretchable intermediate section which will yield sufficiently to take up the extra stretching of the stocking. Thus the more common expedients include picot work at 25 intervals or the knitting of a mesh for accomplishing the same purpose.

As is well known in the art, hosiery made of silk for women is generally knitted from silk thread or yarn, each of which is composed of 30 anywhere from two to seven or even more fine silk filaments. In accordance with this invention, the material is knitted on a flat bed knitting machine of the usual type having at least three yarn carriers for the main body of the 35 stocking. It is understood, of course, that any odd number of carriers may be utilized. Assuming that three carriers are used, one carrier feeds an elastic thread while the other two carriers feed silk threads. The elastic portion is 40 knitted in the stocking, preferably just below the welt, although any other location may be provided.

In accordance with this invention, I preferably use an elastic yarn, one form of which is available in the trade under the name of Lastex and generally consisting of a rubber filament wound with fabric such as silk, cotton or any other material. This composite thread, hereinafter referred to as an elastic thread, is preferably of a 50 size of the same order as the silk thread used in the knitting of the stocking.

In the actual knitting, it is understood of course that the thread or yarn is operated upon while in a moist condition. In the event that 55 cotton covered rubber is used as the elastic

thread with two or more silk threads as the others, it may be necessary to use some vegetable oil rather than water for moistening the various threads. Thus cottonseed or soya bean oil may be used for moistening the elastic thread and then the knitted article cleaned with a suitable oil solvent to remove the oil. In the event that oil is used, it is preferable to leave it in the thread as short a time as possible to prevent any undesirable action on the rubber. Of course, 10 any of the oil resistant rubbers may be used as the core of the elastic thread in which case no special precautions on oil removal are necessary.

If the elastic thread is silk covered or covered 15 with some other material which does not absorb excessive amounts of water, then the conventional water moistening may be relied upon.

A band having any number of courses may be provided in accordance with the following plan. 20 For practical purposes in a woman's stocking this band should be at least about one inch in width and preferably greater. This stretchable band consists of the following in the order of knitting: one or more silk thread courses of conventional knitting, then one course of elastic thread of conventional knitting, then a course 25 of silk thread with the loops elongated or loosened, then a silk thread course of ordinary size loops joined to the loose loops in a picot 30 fashion so that two loose loops are caught by one ordinary loop. After this course of silk thread, the elastic thread course may be repeated, or if desired, additional silk courses may be repeated prior to the elastic thread course. 35

The elongated loops are preferably of such a size that in the normal condition of the finished fabric the distance between the two adjacent courses having the picot interloops is about the same as between every other normally spaced 40 loop. Hence in a 45 gauge machine, there are thirty needles to the inch and sixty threads per inch. By elongating the loops as above and providing a picot interloop, a space of about one-thirtieth of an inch is produced between the 45 picot interlooped courses. The space has about the same dimension along the course due to the halving of the number of actively engaged loops.

It is understood, of course, that the figures given above are illustrative and may be varied 50 within wide limits. Thus two interlooped courses of elastic thread may be provided or several sets of picot interlooped courses may be provided or both in combination may be provided. Another factor having substantial bearing on the loop 55

size is the relative sizes of elastic and silk thread. An elastic thread, heavy in comparison to the silk thread, will naturally tend to pull down the silk loops when the tension on the elastic thread is released. Furthermore, the slightest pull on the knitted fabric in any direction tends to distort the loops and proportions between loose loop and normal loop sizes.

I have observed that the knitted fabric made 10 in accordance with my invention yields equally well in all directions. Thus, when tension along the course length is present, the elastic thread tends to straighten out and pulls the loose loops longer. When tension transverse to the course 15 length is present, the loose loops tend to pull the elastic threads out from the course. In practice, both the loose loops and elastic thread yield due to the tendency of the fabric to narrow when lengthened and vice versa. With a pattern of 20 course as described, an elastic mesh is provided which yields substantially in all directions.

In the knitting operation it is preferred to have the elastic thread with just enough tension to prevent sagging of the thread. In practice the 25 elastic thread has a diameter equal to or about two or three times that of the silk thread so that the loops of elastic may be somewhat thicker than the silk loops.

The invention here is restricted to knitting 30 with fine thread or yarn of the order of 42 gauge or more, it being understood that this number represents the number of needles for an inch and a half. It is further understood that the knitting is restricted to the flat work used in the 35 manufacture of full fashioned hosiery, for example.

The actual carrying out of this process on a knitting machine of the flat bed type is obvious 40 after the pattern of courses and picots has been determined upon. Inasmuch as a standard knitting machine is used, no specific description of the machine will be made apart from the general figure shown in the drawings.

Referring to the drawings:

Figure 1 shows a view of a woman's hose; 45 Fig. 2 shows a detail enlarged view of the elastic band with a portion of the edge;

Fig. 3 is an enlarged detail view of an elastic thread; and

Fig. 4 is a diagrammatic view of a flat-bed 50 knitting machine head.

Referring to Fig. 1 there is shown a hose having a leg portion 10 with foot portion 11 and an elastic section 12 which is supported between leg 55 portion 10 and a welt 13. Inasmuch as the manufacture of full-fashioned hosiery is well known, no further details in regard to the shape of the blank and the seam need be given.

The leg portion 10 is knitted on a flat-bed 60 machine of the standard type having a plurality of heads, one of which is a diagrammatically shown in Fig. 4. This head comprises the usual frame portion 15 carrying a bank of needles 16 and points 17 and is provided with three yarn carriers 18, 19 and 20. A minimum of three 65 yarn carriers is necessary for carrying out this invention. However, this number may be increased by units of two to any other odd number of yarn carriers.

The yarn carriers 18, 19 and 20 each pull the 70 yarn or thread through suitable moistening means 1, 2 and 3 such as cups with wicks. The moistening medium, as pointed out before, may be water or vegetable oils or any other preparations well known in the art.

Two of the yarn carriers, as for example, 18 and 19 in Fig. 2, have ordinary silk thread or yarn. Yarn carrier 20 is adapted to supply elastic thread, a small section of which is shown in enlarged detail in Fig. 3. This elastic thread comprises a core 21 of rubber upon which is wound a silk or any other fabric thread 22 in one direction and if necessary a second thread 23 superimposed on 22 and wound in the opposite direction. Inasmuch as such threads are well known in the art, further description is unnecessary.

Referring to Fig. 2, there is shown a course 25 of silk thread with the loops knitted in a normal manner. Engaging the loops of course 25 is a 15 course 26 of elastic thread. This is followed by a course 27 of silk thread whose loops are elongated and interlooped with the next course 28 in a picot fashion. Thus two loose loops of course 27 are engaged by one loop of course 28. After silk 20 course 28, which is a conventional course as far as loop size is concerned, an elastic thread course 29 follows and then a loose silk course 30, similar to course 27. As shown in dotted outline, course 25 may be knitted by thread from carrier 18, while 25 courses 26 and 27 are supplied by carriers 20 and 19 respectively. As indicated by the arrow, the courses as given above are in the order of knitting.

It will be noted from Fig. 2 that the elastic section or band is divided by a line into the elastic 30 portion proper 33 and a selvage portion 34. The knitting in the selvage is preferably carried out in a regular loop formation on all courses with no picot work at all. It is understood, of course, that if desired the picot work can be extended to 35 the very edge of the knitted fabric, but in order to provide a strong section for seaming, it is preferred to provide the portion 34 as shown.

The manner in which the leg portion 10 merges into the adjoining sections is of no importance. 40 In the event that the elastic section 12 is knit with a heavier silk thread or other fabric thread than the body 10, it is preferable to provide a plurality of courses of ordinary knitting with the silk prior to the picot part. This, however, may 45 be varied to suit individual needs.

As previously pointed out during the knitting operation it is preferred to supply the elastic thread under just enough tension to prevent sagging. If the elastic thread is tensioned excessively there is some danger of snagging of the needle as well as a puckering of the finished fabric. However, under certain conditions it may be advisable to supply the elastic thread under 55 some tension.

It is understood that the proportions in loop shown on the drawings and given by way of example are merely suggestive. Because of handling materials which yield readily, it is difficult and unnecessary to set forth precise details. Uniformity in any one product is necessary but variations among the products is permissible.

What is claimed is:

A method of flat knitting a strain absorbing section in a stocking with fine yarn on a machine 65 having a needle gauge of at least 42 which comprises knitting one course with yarn, knitting a succeeding course with an elastic thread with all of the loops normally engaged between said two courses, knitting the succeeding two courses with 70 yarn and providing a picot interloop therebetween and repeating this cycle of courses, said last yarn course being the first yarn course in a succeeding cycle.

NICHOLAS F. LAHR.
